UNITED STATES PATENT OFFICE

ANGUS F. HANNEY, OF NORWOOD, OHIO, ASSIGNOR TO THE AMERICAN LAUNDRY MACHINERY COMPANY, OF CINCINNATI, OHIO, A CORPORATION OF OHIO

IDENTIFYING MECHANISM

Application filed May 28, 1930. Serial No. 456,460.

The invention disclosed in this application relates to identifier mechanism and particularly to the form wherein a plurality of tags or article markers are attached to laundry articles to identify them in their course through laundry treatment.

Heretofore there have been identifying systems employed in the identification of laundry work but these systems have not been of a character such that a sufficient number of different markers are provided for handling the normal load of a commercial laundry. The reason for the limitation has been that where the warding principle between the markers and racks or the like is used, the tag itself could be reversed or inverted thus reducing the possible number of identifying combinations. In other words, there was no means provided which required each marker to be presented to the receiving device or rack in a predetermined non-reversed position. It must be remembered that the tags must be of relatively thin metal and cannot be of any great thickness or have projections at any point because they must pass through such machines as the flatwork ironer, etc. Hence, almost any one of the markers previously employed could not only be inverted but could be reversed and be presented improperly to the receiving device or rack thus producing errors.

The object of the present invention therefore is to provide the tags with means such as master wards or recesses, or the like, which cooperates with other means associated with the receiving device or rack so that the marker or identifier may be applied to the receiving device or rack in one position only, and that a predetermined non-reversed, non-inverted position.

Other features of the invention will be brought out in the following description, drawings and claims.

Referring to the drawings, Fig. 1 is a side elevation of a rack with a marker applied to it; and Fig. 2 is a front elevation.

In the drawings, 1 represents a main support adapted to be secured to a wall or any other similar structure. This main support has an outwardly projecting rectangular flat

bar 2 adapted to form the receiving or supporting device or rack. Above this device and parallel to it is a master bar 3 substantially coextensive with the bar 2 but preferably slightly shorter, as shown, so that the tag may be lodged first upon the bar 2 and brought into engagement with the end of a master bar 3. This master bar may be placed in the position shown in the dotted line position indicated at 4, or in the dotted line positions indicated at 5 and 6, in which case the support 1 would be arranged to carry these bars in their proper position. With such an arrangement there could be many differently masterd receiving devices or racks without duplication.

The bar 2 is also provided with suitable wards 7, 8 and 9, which by being located in different transverse positions provide for a large number of combinations for identifiers. There will be one rack for each of the combinations made possible by the wards 7, 8 and 9 and the master bar 3.

Cooperating with these receiving devices or racks are the markers, shown at 10, which may be of any suitable shape and provided with a central opening 11 having openings receiving the wards 7, 8 and 9, for example. This marker is also provided with a recess, indicated at 12, for cooperation with the master bar 3. Secured to the marker 10 is a ring 13 receiving a pin 14 or other device for securing the marker to the article.

In the use of this embodiment of the invention the several receiving devices or racks are secured to the wall or the like in proper order and each bar and its group of markers have their own identifying indicia stamped or otherwise printed upon them. First the markers are applied to the several articles of laundry and pass through the several treatments. They are sorted by the operator grasping the markers, seeing what indication there is upon them, and placing them upon the proper rack. Here, however, the placing of a tag upon its proper rack is insured by reason of the fact that it can only go on in a predetermined non-reversed position on one rack and the use of the individual wards and recesses as well as the master bar

and the master recess, permit of a large number of combinations and prevent the application of the wrong marker to the wrong rack.

Having described my invention what I

5 claim is:

1. In combination with an assorting apparatus including a supporting device embodying a bar having wardings thereon and a master bar in proximity therewith, a tag attachable to the article to be assorted having an opening whereby it may be disposed on said supporting bar, openings adapted to cooperate with the wardings on said supporting bar, and a recess for cooperation with said master bar, said master bar being so disposed relative to said supporting device as to require positioning of the tag in one predetermined non-reversed position to be positioned on said supporting device.
- 20 2. In combination with an assorting apparatus including a supporting device embodying a bar having wardings thereon and a master bar in proximity therewith, a tag attachable to the article to be assorted and having an opening whereby it may be disposed on said supporting bar, openings adapted to cooperate with the wardings on said supporting bar, and a recess disposed adjacent the outer periphery of said tag for cooperation with said master bar, said recess being so disposed on said tag and said master bar being so disposed relative to said supporting device as to require positioning of the tag in one predetermined non-reversed position to be positioned on said supporting device.
- 30 3. In combination with an assorting apparatus including a supporting device embodying a bar having wardings thereon and a master bar in proximity therewith, a tag attachable to the article to be assorted and having an opening whereby it may be disposed on said supporting bar, openings adapted to cooperate with the wardings on said supporting bar, and a recess disposed adjacent the outer periphery of said tag for cooperating with said master bar, said recess being so positioned on said tag, said master bar being so disposed relative to said supporting device, and said openings in the tag adapted to cooperate with the wardings on said supporting device being so disposed as to require positioning of the tag in one predetermined non-reversed position to be positioned on said supporting device.

55 In testimony whereof I hereby affix my signature.

ANGUS F. HANNEY.
